FIG. 4.

FIG. 5.

UNITED STATES PATENT OFFICE.

JOE S. MACK, OF CALIPATRIA, CALIFORNIA.

WAGON-REACH.

1,336,645.

Specification of Letters Patent.

Patented Apr. 13, 1920.

Application filed October 13, 1919. Serial No. 330,475.

To all whom it may concern:

Be it known that I, JOE S. MACK, a citizen of the United States, residing at Calipatria, in the county of Imperial and State 5 of California, have invented new and useful Improvements in Wagon-Reaches, of which the following is a specification.

My object is to make an improved wagon reach, and my invention consists of the 10 novel features herein shown, described and claimed.

Figure 1 is a side elevation of a wagon provided with a reach in accordance with the principles of my invention, the view being taken looking in the direction indicated 15 by the arrow 1 in Fig. 2.

Fig. 2 is a top plan view looking in the direction indicated by the arrow 2 in Fig. 1.

Fig. 3 is a vertical longitudinal sectional 20 detail on the line 3—3 of Fig. 2 and looking in the direction indicated by the arrows.

Fig. 4 is a rear elevation of the rocker as seen looking in the direction indicated by the arrow 4 in Fig. 1.

Fig. 5 is a diagrammatic view illustrating the operation of turning the wagon and bending the reach upon the secondary king bolt.

The front reach member 1 has a notch 30 crosswise of its lower face and the front axle 2 fits in the notch. The front reach member 1 has a notch in its upper face and the front bolster 3 fits in the upper notch, so that when the bolster 3 is secured to the 35 axle 2 the member 1 is rigidly held. The front axle hounds 4 and 5 fit across the front axle 2 and are held in place by the front bolster 3, said hounds being inclined relative to a longitudinal line. The tongue 40 6 is mounted between the forward ends of the hounds 4 and 5 and the hounds 4 and 5 extend a considerable distance backwardly from the axle 2.

The rocker 7 fits upon the front bolster 3 and the king bolt 8 is inserted downwardly through the rocker 7, through the front bolster 3, through the front reach member 1 and through the front axle 2. The rear portion of the front reach member 50 1 is cut away on its top and bottom to make a guide tongue 9.

The rear reach members 10 and 11 fit against the upper and lower faces of the tongue 9. Straps 12 and 13 are secured to the top and bottom of the body portion of the front reach member and extend back-

wardly on top of and below the rear reach members 10 and 11. A secondary king bolt 14 is inserted downwardly through the strap 12, through the rear reach member 10, 60 through the tongue 9, through the rear reach member 11 and through the strap 13 and is held in place by a cotter 15.

The slider 16 connects the rear ends of the hounds 4 and 5 and the rear end of the 65 tongue 9 and passes between the rear reach members 10 and 11. A spacing block 17 is placed between the rear reach members 10 and 11 behind the slider 16 and a U-clip 18 is inserted downwardly straddle of the members 10 and 11, through the ends of the block 17 and through a washer plate 19, and nuts 20 are applied to the clip below the washer plate 19 so as to hold the members 10 and 11 rigidly together at their central portions. The extreme rear end 21 of the member 10 slides between the rear axle 22 and the rear bolster 23. 70

The rear end of the member 11 is spaced 75 from the member 10 by a block 24. A U-clip 25 is inserted downwardly straddle of the member 10 through the ends of the block 24 straddle of the member 11 and through a washer plate 26, and nuts 27 are applied to the lower ends of the clip 25 80 85 against the washer plate 26.

Rear hounds 28 and 29 are connected together at their forward ends by a block 30 and the block 30 rides upon the member 10. A U-plate 31 is placed under the member 90 10 and the ends of the plate are connected to the forward ends of the hounds 28 and 29 to make a bearing through which the member 10 slides. A plate 32 is secured to the upper faces of the forward ends of the 95 hounds 28 and 29 across the block 30 and a pin 33 is inserted downwardly through the plate 32, through the block 30, through the member 10 and through the plate 31 to connect the rear axle 22 to the reach. 100

A series of pinholes 34 is formed through the member 10 so that the pin 33 may be removed from one hole and the rear axle 22 moved forwardly or backwardly and the pin reinserted through the desired hole 34 105 to adjust the length of the reach.

The secondary king bolt 14 is some distance behind the front axle 2 and makes it possible to turn the axle 2 almost to a right angle to the rear axle 22. Rollers 110 35 and 36 are mounted upon the rocker 7 at its ends to support the load and allow the

load to move forwardly and backwardly upon the rocker as required in making a turn. Obviously the distance between the front axle 2 and the rear axle 22 is constantly changing as turns are made.

Among the advantages of this construction are the facilities for making short turns, the double construction produced by the rear reach members 10 and 11 spaced 10 apart by the blocks 17 and 24 and secured together by the clips 18 and 25, and the slider 16 operating between the reach members 10 and 11.

Various changes may be made without 15 departing from the spirit of my invention as claimed.

I claim:

1. A wagon reach construction comprising a front reach member fixed to the front 20 axle and having a tongue extending backwardly, a slider connecting the rear ends of the front hounds and the rear end of the tongue, rear reach members fitting above and below the tongue and slider, a pin 25 connecting the forward ends of the rear reach members to the forward end of the tongue, spacing blocks between the rear

reach members, and means for securing the rear reach members to the spacing blocks.

2. A wagon reach construction comprising a front axle, a front reach member notched on top and bottom and fitting the front axle, a front bolster fitting in the upper notch and secured to the front axle, the rear end of the front reach member 35 forming a guide tongue extending backwardly, front hounds fixed between the front axle and the front bolster and extending backwardly, a slider connecting the rear ends of the front hounds and the rear 40 end of the tongue, rear reach members fitting above and below the tongue and slider, a secondary king bolt connecting the front ends of the rear reach members to the front end of the guide tongue, spacing blocks between the rear reach members back of the slider, means for holding the rear reach members to the spacing blocks, rear hounds, and a pin for connecting the rear hounds to the reach, there being a plurality of holes 45 through the reach for the pin.

In testimony whereof I have signed my name to this specification.

J. S. MACK.
